UNITED STATES PATENT OFFICE

LEONARD L. STEED, OF JOHNSON CITY, NEW YORK, ASSIGNOR TO ENDICOTT JOHNSON CORPORATION, OF ENDICOTT, NEW YORK, A CORPORATION OF NEW YORK

DESIGN FOR A TEXTILE FABRIC OR THE LIKE

Application filed January 9, 1930. Serial No. 34,060. Term of patent 14 years.

To all whom it may concern:

Be it known that I, LEONARD L. STEED, a citizen of the United States, residing in the village of Johnson City, in the county of Broome and State of New York, have invented a new, original, and ornamental Design for Textile Fabric or the like, as shown in the accompanying drawing, forming part of this specification.

The figure is a portion of textile fabric or the like showing my new design, which is intended to be applied as a plurality of spaced units.

I claim:

The ornamental design for a textile fabric or the like, substantially as shown and described.

LEONARD L. STEED.
